CLAIM

The ornamental design for a hydromassage bath tub, as shown.

DESCRIPTION

FIG. 1 is a perspective view taken from the top front, and left side of a hydromassage bath tub showing our new design; FIG. 2 is a top plan view thereof;

FIG. 3 is a cross-sectional view taken on line 3—3 of FIG. 2; and,

FIG. 4 and 5 are cross-sectional views taken on lines 4—4 and 5—5, respectively, of FIG. 3.
